POWDER PUFF

Maurice Levy, New York, N. Y.

Application June 6, 1932, Serial No. 615,487

2 Claims. (Cl. 132—78.5)

My invention relates to a new and improved powder puff.

One of the objects of my invention is to provide a powder puff having a base, and a piece of pile fabric whose base portion is connected to said base.

Another object of my invention is to provide a puff which is free from stitches at the edge thereof.

10 Another object of my invention is to provide a puff in which the pile fibres extend beyond the edge of the base.

Other objects of my invention will be set forth in the following description and drawing which 15 illustrates a preferred embodiment thereof, it being understood that the above general statement of my invention is intended to generally explain the same and not to limit it in any manner.

Fig. 1 diagrammatically illustrates how a piece 20 of pile material is cut from a sheet of said pile material.

Fig. 2 is an elevation of the reverse side of the article shown in Fig. 1.

Fig. 3 is a sectional view of the completed 25 article.

For many years thin powder puffs have been manufactured on a large scale for use in vanity cases, and the like. Such powder puffs have been made of a piece of woven pile fabric, said pile fabric having a base portion and pile fibres extending from one side of said base portion. Such pile fabrics have been woven on looms of well known construction for many years, and they require no special description.

30 In making a thin powder puff, it has been customary to cut out pieces of the base material, by means of dies and to then connect a base, made of silk or other closely woven fabric, to the base portion of the pile fabric. Such connection has been previously accomplished by means of 35 stitches, which were objectionable especially when the puff was applied near the eyes of the user.

Likewise, when circular pieces (or pieces of 40 other shapes) were cut from a single large sheet of pile fabric by means of dies, the pile fibres were laterally spread out by the cutting edges of the dies, so that the dies sheared off the pile fibres adjacent the edge of the cut-out piece. Hence, 45 the completed powder puff did not have the pile fibres adjacent the edge thereof.

According to my invention, a sheet of pile material is cut by means of scissors or a cutting knife, or any other suitable cutting tool (without 50 the use of dies), so that the cut extends through

the base portion of the woven pile fabric, without cutting off any of the pile fibres. For example, and as shown in Fig. 1, a circular cut may be formed in the base portion 1 of the woven pile fabric, without cutting any of the pile fibres 2. 60 That is, the material is severed by forming a cut in the woven base portion so that the cutting tool or tools do not touch the pile fibres and do not sever the pile fibres. The piece of pile material which is thus separated is then connected to a 65 base 3 which is made of silk or any other suitable closely woven material.

I do not wish to be limited to the use of woven material, or to the use of any specific material, for making the base 3 of the puff. For example, 70 it is well-known to make a puff from two pieces of pile fabric.

The base 3 of the puff is connected to the base portion 1 of the piece of pile fabric, by means of a suitable adhesive, this being preferably a latex 75 adhesive. This latex adhesive can be intermixed with a vulcanizer, and with a suitable accelerator or accelerators, so that when the latex is dried, it is vulcanized at ordinary room temperature, or preferably at an elevated temperature of 216° F. The latex adhesive has the fluidity of ordinary latex, and it is applied to the closely woven base portion 1 and also to the base 3, and the base 3 and the base portion 1 are then applied to each other with suitable pressure. 80 The base portion 1 is closely woven so that the adhesive does not penetrate to the fibres 2, said adhesive being confined substantially within the base portion 1.

The bases 1 of the pieces of pile fabric and their 85 adhering bases 3 are placed in a hot air chamber which is maintained at a temperature of 216° F., until the latex has dried, thus forming a very thin and flexible layer of vulcanized rubber which connects the base 3 to the base portion 1. This heating operation also spreads out the fibres 2, as shown in Fig. 3.

Fig. 1 illustrates in exaggerated form how the pile fibres 2 extend up to and beyond the edge of the corresponding base portion 1, especially when 90 said pile fibres are spread out by pressure.

After the adhesive has been set, the puffs can be subjected to the action of steam at a temperature of about 216° F., and at a pressure of ninety pounds per square inch for a period of 105 twenty minutes. This causes the pile fibres to spread out as shown in Fig. 3.

I do not wish to be limited to any particular adhesive.

Likewise, the claims for the article of manufac-

110

ture are not to be limited to any particular method of producing the same.

The latex adhesive which is utilized can be in concentrated form so that it can be readily dried. Since the adhesive is confined to the base 5 of the woven pile fabric, the outer ends of the pile fibres are free from said adhesive.

The invention is not to be limited to the use of a fabric which is woven so as to produce a pile because a pile may be produced by means of a napping machine upon a piece of suitable fabric.

I have shown a preferred embodiment of my invention, but it is clear that numerous changes 15 and omissions can be made without departing from its spirit.

I claim:—

1. A puff which includes a piece of cut pile fabric which is connected to a second piece of

20

fabric, said pile fabric having a base portion which has pile fibres at one face thereof, the base of said pile fabric being connected to said second piece of material by vulcanized latex, the vulcanized latex which is applied to said pile fabric being substantially confined to its base portion.

2. A puff which includes a piece of cut pile fabric which is connected to a second piece of 85 fabric, said pile fabric having a base portion which has pile fibres at one face thereof, the base of said pile fabric being connected to said second piece of material by vulcanized latex, the vulcanized latex which is applied to said pile fabric being substantially confined to its base 90 portion, the pile fibres in uncut form extending to and beyond the edge of the puff.
